CLAIM

The ornamental design for a bracket as shown and described.

DESCRIPTION

1. Bracket

Fastening, supporting or mounting device, not included in other classes.

1.1 is a perspective view of the bracket, showing the claimed design;

1.2 is a front view thereof, the rear view being identical;

1.3 is a top view thereof; and

1.4 is a right side view thereof, the left side view being identical.

1 Claim, 4 Drawing Sheets(56)
